UNITED STATES PATENT OFFICE.

GEORG STEINMETZ, OF CHARLOTTENBURG, GERMANY.

LOOSE-LEAF-SUSPENDING FILE.

Application filed May 27, 1926, Serial No. 112,076, and in Germany October 19, 1925.

This invention relates to a device for suspending loose folded sheets interchangeably in vertical files and it is one of the objects of the invention to provide a suspension file of this character which shall be simple and effective in use and to which index matter for registration purposes can easily be applied so as to be easily accessible under any circumstances.

10 The essential feature of the invention consists in that the sheets to be suspended are bent over at one edge and introduced with their folded margins into a jaw formed by a bent-over portion of a back plate, against which they are firmly pressed by means of a front plate, rail, or some other rigid member. The whole arrangement may be bodily suspended, and the arrangement of the clamping device is such that it will grip the 20 sheets with greater force the heavier the pile of the suspended sheets is. The clamping device and the suspension means may be integral with each other, or separate as desired.

25 The preferably reinforced ledge formed by the turned-over portion of the back plate enables a secure hold of the suspended sheets over the entire length of the back plate. The visible top surface of the ledge on the 30 back plate is preferably provided with a suitable space for the application of index matter for registration purposes which is of particular advantage as each of these ledges is easily observable on account of its slanted arrangement as will be more fully described.

In the drawings several modifications of the invention are illustrated by way of example.

40 Fig. 1 shows the device as used with a spring clip serving as a clamping member and suspension for the sheets to be suspended.

Fig. 2 is a vertical section therethrough.

45 Fig. 3 illustrates the arrangement of a loosely applied counter-pressure member.

Fig. 4 illustrates the use of a scissors-shaped clamp serving at the same time as a suspension member.

50 Fig. 5 shows a loosely inserted plate having a bent-over edge to serve as clamping member.

Figs. 6 to 10 represent several modifications in which plain counter-pressure members are employed.

55 Referring first to the modifications shown

in Figs. 1 to 5, *a* denotes the back plate and *b* the cover plate, both of which plates are bent or folded over along the whole length of their upper edges and are provided with a suspending device serving at the same time for the clamping of the sheets. The ledge *a'* formed by the bent-over portion of the back plate *a* is preferably provided over its entire length with a reinforcing strip *x* made of metal, while the ledge *b'* of the cover plate *b* which is contained within the ledge *a'* need only be reinforced over that portion of its length which is in engagement with the clamping device, which is done by a strip *g* similarly disposed as is strip *x*. The provision of the member *b'* with a metallic strip serves the particular purpose of enabling the said member better to resist the pressure exerted by the clamping device and to reduce the friction which is entailed by the free ends of the resilient clips engaging therewith. The sheets to be filed away in the device are likewise bent over at one edge and inserted between the back plate *a* and the cover plate *b*, with their folded margins between the ledges *a'* and *b'* respectively.

55 In the devices shown (except Fig. 3) the arrangement of the clamping devices is such that their pressure increases in direct proportion to the increase of the weight of the suspended sheets. Thus the grip exerted by the clamps will be all the firmer the heavier the weight of the suspended sheets becomes.

In the arrangement according to Figs. 1 and 2 the clip which forms the clamping device is bent from a continuous wire or the like and may have any convenient shape.

The example of Fig. 1 illustrates a shape 95 of the clip which has proved to be of particular advantage for comparatively broad suspending devices and which is attached to the device at three neutral points, that is to say at points at which the spring clip exerts no clamping action.

A rivet at *c* is used to attach the clip at its centre to the back plate *a*, while rivets at *d* serve to fasten the clip at two points to the member *a'*.

Hooks *e* formed of the same length of wire with the clip proper are used as suspension means for the entire device, while the free ends of the clip are coiled into the shape of a spiral and sprung under the ledge *b'* of the cover plate or strip *b*, where it preferably rests against the metallic reinforcing strip *g* arranged at that place. The ends *f* are off.

set as shown in Fig. 2 so as to prevent their lying against the front of the ledge a' and avoid undue friction upon same. Apart from the reduction of the friction enabled by the provision of the metallic reinforcing strip this way of offsetting the ends of the spring clip ensures the said ends always taking their most effective positions due to their form and their resiliency in action.

10 According to the modification shown in Fig. 3 hook members h are fixed to the back plate a at h' , to which hooks the spiral-shaped clips k are displaceably attached as by means of rings or eyelets i . In order to 15 hold the sheets to be suspended the spiral ends of the said clip are sprung under the ledge b' of the cover plate b .

The arrangement shown in Fig. 4 illustrates a scissors-like clamping device, having one of its legs attached to the back plate a while the other leg m is turnable about the pivot n and adapted to grip with its hook-shaped end under the fold b' of the cover plate b . The clamping action of the free end 25 can be made to act either in the direction of the strip or ledge a' , i. e. in the plane of the sheets, or at right angles thereto. Rings or eyes n at the upper ends of the clip serve to suspend the entire device together with the 30 sheets secured thereby.

In the arrangement according to Fig. 5 the clamping action is obtained by a plate o of which the lower edge is bent over and caused to grip under the ledge b' . The said 35 plate o is displaceable in relation to another plate o' which is attached to the back plate a and to which it may be secured by means of a thumb screw p . The device may be suspended by means of a hook q attached to 40 either of the said plates.

The peculiar arrangement of the suspending devices described with their slanted and externally visible ledges a' admirably lends itself to the application of index matter indicating the contents of each of the files. It is evident that the slanted arrangement of these ledges, which can clearly be observed in Fig. 2, renders each of them easily visible even when a larger number of the files are 50 arranged one after the other.

In the modifications illustrated in Figs. 6 to 10 no bent-over cover plates are employed, and any other type member may be used to press the loosely inserted folded sheets 55 against the reinforced ledge of the back plate a , such as a flat bar, or the like.

Fig. 6, for instance, shows the simple arrangement of suspending eyelets r secured to the back plate, by riveting or the like, by 60 means of which the device may be hung up, while a flat bar or plate s is used firmly to press the sheets against the ledge a' . In this operative position the said bar s is fastened to the ledge a' as by means of spring clips t or the like. The spring clips t each comprise

a shell t' or the like, secured in any desired manner to the folded part a' , and the coiled spring u' in the shell urges the hooked end of the clip t upwardly. In order to operate the locking spring clip it is only necessary to withdraw the hooked end outwardly against the spring tension and turn the hook either inwardly to grasp the plate or rail s when released, or outwardly to free such member s . The bar or plate s may be entirely separate 75 from the other parts of the device, or it may be movably fixed with one of its ends to the back a as by means of a chain, a cord, links, or any other suitable means as indicated at s' in Fig. 7 for example, so that only the 80 other free end need be locked when in use.

As an alternative the flat rail or bar may be made of two parts as shown in Fig. 8, and each part may be secured to the back a at its outer end in a manner similar to that 85 referred to in connection with Fig. 7, in which case the locking means must be arranged at the centre at which the inner ends of the bar meet or overlap.

A further alternative is the combination 90 of the suspension means with the clamping member as indicated in Fig. 9 for example, in which a kind of lazy tongs arrangement is employed. The suspension levers w are provided with hooked ends w' and are pivoted at x . These levers are in connection, as by means of links y , with a centrally pivoted pair of double hooks z adapted to engage with one of their hooked ends over the top of the ledge a' and with their other end under the lower edge of same, or against any other member used for the purpose. 100

Fig. 10 illustrates an arrangement in which the suspension means in the shape of eyelets u are fixed to the cover plate s . Resilient holding members v are likewise fixed to the said plate s and adapted to pass around the ledge a' . These members v keep the sheets and the entire device together and prevent the bar s from slipping out of the 110 fold a' when taking the entire device down from its supports.

What I claim is:—

1. In a loose leaf vertical file for suspending folded-over sheets, a back plate, a bent-over top ledge forming part of the back plate, a cover plate, clamping means to press one of the said plates against the other, and suspension means to suspend the device cooperating with at least one of the said plates. 115

2. In a loose leaf vertical file for suspending folded-over sheets, a back plate, a bent-over top ledge forming part of the said back plate, a cover plate, a bent-over top ledge to the cover plate to be received within the bent-over top ledge of the back plate, clamping means to press one of the said plates to the other, and suspension means for the device cooperating with at least one of the said plates. 120 125 130

3. In a loose leaf vertical file for suspending folded-over sheets, a back plate, a bent-over top ledge integral with same, a cover plate ledge to be received within the bent-over top ledge of the back plate, a reinforcing layer applied to each of the said ledges, resilient clamping means to press the cover plate ledge into firm contact with the back plate ledge, and suspension means for the device cooperating with at least one of the said plates.
4. In a loose leaf vertical file for suspending sheets, a back plate, a bent-over top ledge to the back plate, a counter-pressure member to be received within the fold of the back plate ledge, resilient clamping means attached to the back plate and acting upon the counter-pressure member, and suspension means for the device, said clamping and suspending means forming one continuous part.
5. In a loose leaf vertical file for suspending sheets, a back plate, a bent-over top ledge to the back plate, a counter-pressure member to be received within the fold of the back plate ledge, resilient clamping means attached to the back plate and acting upon the counter-pressure member, and suspension means for the device, said clamping and suspending means forming one continuous part.
6. In a device for vertically suspending loose sheets, a back plate having a bent-over top ledge, a counter-pressure member to be received within the bent-over ledge, a resilient clip fastened to the back plate and having its free ends arranged to grip under the bent-over top ledge and acting upon the counter-pressure member to thereby exert a pressure against the said ledge, and suspension means to suspend the entire device and to cooperate with the clip whereby the action of the said resilient clip is such that the clamping increases with the weight of the sheets suspended.
7. In a device for vertically suspending loose sheets, a back plate having a top ledge bent over from the back at an inclination thereto, a cover plate, said top ledge adapted to receive index matter, means for clamping the sheets to be filed, within the bent-over top ledge between the plates, and means cooperating with one of said plates to bodily suspend the entire device.

In testimony whereof I affix my signature.

GEORG STEINMETZ.
